ATT. 5.

UNITED STATES PATENT OFFICE

2,567,143

FUEL SYSTEM FOR HEATERS

Ernst Justus Bodensieck, Euclid, Ohio, assignor
to Thompson Products, Inc., Cleveland, Ohio,
a corporation of Ohio

Application December 6, 1946, Serial No. 714,605

4 Claims. (Cl. 237—12.1)

1

This invention relates to a system for maintaining a constant ratio of two propelled fluids in spite of variations in speed of the fluid-propelling means.

Specifically, this invention relates to a heater assembly especially adapted for motor vehicles such as buses and the like.

While the invention will hereinafter be specifically described as embodied in a bus heater system, it should be understood that the principles of this invention are generally applicable for the automatic control of fluid flow to maintain a constant ratio or proportion of two different fluids in spite of the fact that variations in speed of the means for propelling the fluids would normally change the ratio or proportion.

In bus heater systems, it is conventional to drive a fuel pump and an air blower from a single electric motor that is energized by current from a generator driven by the internal combustion engine which drives the bus. The voltage of this current varies considerably since the bus motor, in normal operation, will drive the generator at widely different speeds. Voltage changes will vary the speed of the electric motor, thereby changing the speed of the pump and the blower. Air flow from the blower varies as the first power of the speed of the motor driving the blower. However, heretofore variation in the speed of the pump has not appreciably changed the rate of flow of the fuel pumped thereby because relief valves have kept a constant pressure on the discharge side of the pump irrespective of speed and the combustion chamber of the heater would receive a relatively constant supply of fuel with a widely varying supply of air. As a result, slowing down of the motor speed frequently produced smoking conditions in the combustion chamber due to inadequate supply of air for thorough combustion. Conversely, speeding up of the motor produced a lean fuel condition in the combustion chamber.

A further deficiency in the known bus heater units existed due to the inability to stop dribbling of fuel into the combustion chamber of the unit during periods of rest. During such times fuel on the discharge side of the pump would drain into the combustion chamber, forming a pool therein which, of course, is highly undesirable for efficient operation.

The present invention not only eliminates the variations in the fuel-air ratio heretofore caused by variations in driving speeds for the air blower and fuel pump, but also eliminates the heretofore-encountered dribbling of fuel into the combustion chamber during periods of rest.

The invention now makes possible the use of a motor speed regulator to vary the rate of heat generation of a heater unit in accordance with ambient temperature conditions.

2

In accordance with the invention, a by-pass around the positive displacement pump is provided with a restricted orifice and the nozzle in the combustion chamber is equipped with a spring-biased shut-off valve that will stop fluid flow as soon as the pump is stopped. The by-pass with the restricted orifice maintains fuel in the discharge line at the desired pressure during operation of the pump at normal speed. At lower speeds of the pump this pressure drops and decreases fluid flow to the nozzle in the exact proportion to match the decreased air flow caused by the reduced motor speed. The orifice thus operates to maintain a constant fuel-air ratio over a wide range of varying motor speeds.

An object of the invention is to maintain a constant air-fuel ratio in a heater system for a bus or the like in spite of variations in speeds of operation of the means driving the fuel pump and air blower.

Another object of the invention is to provide a system for maintaining a constant ratio of propelled fluids irrespective of variations in speeds of operation of the devices propelling the fluids.

A still further object of the invention is to provide a control system for supplying different fluids in a desired ratio even when different means propel the fluids and have different flow rates when driven at different speeds.

Another object of the invention is to provide a fuel system for a heater or the like wherein a predetermined pressure must be established before fuel can be sprayed, and wherein the possibility of spraying fuel for very short periods of time insufficient to establish combustion is eliminated.

Other and further objects of the invention will be apparent to those skilled in the art from the following detailed descriptions of the annexed sheet of drawings which, by way of a preferred example only, illustrate one embodiment of the invention.

On the drawings:

Figure 1 is a diagrammatic view illustrating a bus heater system.

Figure 2 is a somewhat diagrammatic view of a portion of the apparatus shown in Figure 1 and illustrating some parts in vertical cross section.

Figure 3 is a view of a shut off valve also shown in Figure 2 but illustrating the valve in opened position.

As shown on the drawings:

As shown in Figure 1, an internal combustion engine 10 drives a generator 11 as is customary through a fan belt connection 12. An electric motor 13 is energized from the generator 11 through wires 14 and drives an air blower 15 which discharges through a duct 16 into the combustion chamber 17 of a heater assembly. The motor 13 also drives a gear pump 18 receiving

fuel, such as kerosene or the like, from a supply tank 19 through an inlet pipe 20. The pressurized fuel from the pump 18 flows through a discharge pipe 21 into a valve unit 22 having a spray nozzle 23 depending therefrom. The valve unit and spray nozzle are arranged so that the spray will discharge into the combustion chamber 17. A by-pass pipe line 24 connects the inlet pipe 20 and the discharge pipe 21 around the pump 18. This by-pass 24 has a housing 25 incorporated therein receiving a screw plug 26 having an integral rod or pin portion 26a thereon, as best shown in Figure 2. A sleeve 27 is press-fitted in the housing and receives the pin 26a therethrough to cooperate therewith for defining a restricted flow passageway 28 in the by-pass. As shown in Figure 2, the plug 26 can be removed from the housing and replaced with a plug having a pin of a different size thereby changing the capacity of the restriction 28.

Water from a tank 29, shown in Figure 1, is supplied to a coil 30 in the combustion chamber 17 to be heated therein and fed to a radiator 31. A fan 32 blows air through the radiator for being heated with the hot water to heat the occupied area of the bus. Water from the radiator 31 is returned through pipe line 33 to the tank 29.

A spark plug 34 projects into the combustion chamber 17 and may be energized in a conventional manner to produce a spark in the combustion chamber 17 to ignite the fuel sprayed therein through the nozzle 23. Air from the duct 16 furnishes sufficient oxygen for the combustion. The spent products of combustion are removed from the combustion chamber through the exhaust pipe 35.

As best shown in Figure 2, the valve unit 22 includes a housing with a bore 36 opening through one end thereof at an internally threaded portion 36a; and opening through the other end thereof at a reduced-diameter portion 36b to provide a shoulder 36c intermediate the ends. A sleeve 37 is inserted in the bore 36 and is bottomed against the shoulder 36c. The discharge tube 21 from the pump 18 is secured in the reduced-diameter portion 36b of the bore and supplies the fuel to the passageway 38 through the sleeve 37. A plunger 39 is slidable in the bore 36 and has a conical face 39a adapted to project into the passageway 38 and to engage the end of the sleeve 37 for sealing the passageway. The plunger has a groove 39b intermediate its ends receiving a rubber seal ring O therein to prevent leakage along the plunger. A lug 39c is provided on the end of the plunger remote from the conical face 39a thereof. A coil spring 40 is bottomed on the plunger around the lug 39c and is compressed by a closure plug 41 threaded into the portion 36a of the bore. A gasket 42 interposed between the end of the housing and the head of the plug prevents leakage out of the bore 36.

A passageway 43 communicates with the bore 39 adjacent the sleeve 37 and connects the bore 39 with the interior of the nozzle unit 23. This nozzle unit 23 includes a head 44 with an orifice 44a in the end thereof. An insert member 45 has a pointed end 45a projecting into the orifice 44a and coacting therewith to atomize fluid.

As illustrated in Figure 3, when the plunger 39 is forced away from the sleeve 37, the full force of fluid pressure in the passageway 38 of the sleeve acts on the full face 39a of the plunger. When the pointed portion of the face 39a seats on the sleeve 37, only a small area of the face is exposed to the pressure in the passageway 38, and

therefore as soon as the pressure in the passageway 38 builds up sufficiently to crack the face 39a off of the sleeve 37, the entire face area is exposed to this pressure and the plunger 39 is immediately retracted beyond the passageway 43. As a result, a very fast-acting valve action is obtained, and the valve only opens to a fully opened position. Therefore, the nozzle 23 either receives full flow from the passageway 38, or no flow at all.

The restricted passageway 28 provided between the pin 26a and the sleeve 27 in the by-pass 24 joins the discharge pipe 21 with the intake pipe 20 and as soon as the pump 18 is stopped the valve 22 is immediately closed by the spring 40 and thus is only subject to intake pressure. As a result, the valve need not seal against residual pump pressures in the discharge line after the pump has stopped.

The restricted passageway 28 provides a fixed orifice so that the pressure in the discharge pipe 21 will be maintained in direct proportion to the speed of operation of the pump. Therefore, when the pump slows down, the pressure in the discharge line 21 will be decreased, and vice versa. The orifice size is selected to maintain a predetermined pressure in the discharge pipe 21 when the pump is operated at normal speed. Under this predetermined pressure, the nozzle will spray fuel into the combustion chamber 17 in the correct burning proportions relative to the air introduced by the blower 15, which is also driven from the same motor that drives the pump. Now, when this motor slows down, the rate of air flow in the combustion chamber decreases as the first power of the decreased motor speed. It follows, therefore, that the present invention maintains the proper fuel-air ratio in the combustion chamber because the nozzle is furnished with a reduced quantity of fuel to maintain the desired fuel-air ratio corresponding to the decreased rate of air flow. Under these conditions, proper combustion will be maintained whereas heretofore, relief valves and the like used in pumps kept a constant pressure on the discharge side of the pump irrespective of the motor speed, thereby maintaining a substantially constant fuel feed irrespective of variations in air flow. As a result, combustion chambers of the structures heretofore provided were frequently flooded with fuel as well as frequently supplied with too lean a fuel mixture.

The valve 22 only opens when sufficient pressure has been developed in the discharge pipe 21, and then opens fully to supply the nozzle without interference. When the discharge pressure falls beneath a predetermined minimum, the valve fully closes and no dribbling of fuel occurs through the nozzle.

Since the fixed orifice arrangement is provided, heretofore-encountered difficulties with movable relief valves, such as improper seating of the valve due to dirt on the valve seat, and the like, have been eliminated.

If desired, a motor speed regulator, such as a rheostat R, or the like, can be included in the lead wire to the motor 13 to select the speed level of the motor for deliberate variation of the rate of air and fuel flow to vary the heat generation of the combustion unit 17. The regulator R, if desired, can be automatically set by a thermal unit T under the influence of ambient temperature conditions. This arrangement will vary the heat release of the system in accordance with the requirements of the space being heated, and is

preferable to the usual intermittent operation of a bus or automobile heater. The speed control arrangement is made possible because the system of this invention maintains an air-fuel ratio suitable for efficient operation over a wide range of flow rates.

The above descriptions will show wherein the invention provides a shut-off valve and restricted orifice arrangement for a fluid flow system to maintain a fixed ratio of propelled fluid even though the speeds of the propelling means for these fluids change and vary their action on the fluid.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A vehicle heating system comprising a variable speed electric motor, an engine driven generator adapted to be carried by the vehicle to energize said motor at variable output voltages, a fuel pump, an air blower, said electric motor forming a common driving means for said fuel pump and said air blower, means to supply wholly liquid fuel to the input side of said fuel pump, a combustion chamber, duct means to supply fuel discharged by said fuel pump to said combustion chamber, inlet means for said combustion chamber to receive air from said air blower, a spring-biased shut-off valve in control of said duct means to seal off the fuel discharged by said pump upon stoppage of the pump, a by-pass connecting the intake and discharge sides of the pump, and a fixed orifice defining means in said by-pass to maintain a constant air-fuel ratio in said combustion chamber as the speed of said electric motor varies during the open period of said valve, said orifice defining means relieving pressure on said valve when said pump is stopped so that said valve will rapidly close and need seal against inlet pressure only.

2. In combination with a motor adapted to be operated at variable speeds by an engine-driven generator means adapted to be carried on a vehicle, a liquid pump driven by the motor, means to provide wholly liquid fuel to said pump, a by-pass around the pump, a spray nozzle, a normally closed spring-biased valve controlling flow of said fuel from the pump into the nozzle, and a constantly open fixed orifice defining means in said by-pass to maintain a pump discharge pressure proportionate with the speed of the motor driving the pump when said valve is open, said by-pass relieving pressure on the valve as soon as the pump is stopped for prompt closing of the valve to avoid dribbling of liquid through the nozzle.

3. In combination with an engine-driven vehicle heater system having a combustion chamber fed by a blower and a positive displacement fuel pump both driven by a common motor en-

ergized by an engine-driven generator means adapted to be carried by the vehicle, a fuel pump by-pass line between the discharge and suction sides of said pump, a fixed orifice in said by-pass line, means to provide wholly liquid fuel to said pump, and burner means to receive fuel from said pump for burning in the combustion chamber, said burner means including a spring-biased valve to seal off the fuel discharged by said pump upon stoppage of the pump, said orifice operable to maintain the air-fuel ratio at the burner means constant when said valve is open and to relieve discharge pressure of said pump upon stoppage of said pump, thereby precluding drip and dribble through said burner means.

4. A heater for engine-driven vehicles comprising a power generator adapted to be driven at variable speeds by the vehicle engine, a motor 20 driven by the generator at speeds responsive to the variable output of the generator, a blower driven by the motor, a pump driven by the motor, a combustion chamber having inlet means to receive air from the blower, a fuel tank supplying 25 wholly liquid fuel to the pump, a nozzle for spraying said fuel into the combustion chamber, a spring-biased valve between said nozzle and said pump, a by-pass around the pump, a fixed restriction in said by-pass, means for igniting fuel 30 in the combustion chamber, means for circulating heat transfer fluid through the combustion chamber to be heated therein, and a radiator heated by said heat transfer fluid, said fixed restriction and said by-pass together constituting 35 a fixed orifice and being constructed and arranged to maintain a desired fuel pressure at the nozzle when said valve is open and during operation of said electric motor at varying speeds in response to variations of output of said generator 40 and to release the fuel pressure at said valve upon stopping said motor, whereby compensation against the decrease in air flow from said blower to said combustion chamber is effected and dribble from said nozzle is precluded.
